E. G. GARTIN

DRILLING MECHANISM

Filed March 13, 1924

UNITED STATES PATENT OFFICE.

ELMER G. GARTIN, OF CLAREMONT, NEW HAMPSHIRE, ASSIGNOR TO SULLIVAN MACHINERY COMPANY, A CORPORATION OF MASSACHUSETTS.

DRILLING MECHANISM.

Application filed March 13, 1924. Serial No. 699,116.

My invention relates to drilling mechanisms.

It has for its object to provide an improved drilling mechanism. Another object is to provide an improved drilling mechanism of the pick hammer type. Another object is to provide improved fluid actuated valve distributing mechanism for the motor. A further object is to provide an improved hammer type drilling mechanism having a hammer piston to one end of which pressure fluid is constantly supplied. A still further object is to provide improved valve mechanism, one movement of which is caused by fluid flowing from the end of the motor cylinder to which constant pressure fluid is supplied.

In the accompanying drawings I have shown for purposes of illustration one form which my invention may assume in practice.

20 In these drawings,—

Fig. 1 is a longitudinal vertical section.

Fig. 2 is a fragmentary side elevation, partly broken away, to show the piston and valve in a different operative relation from that shown in Fig. 1.

In the illustrative form of my invention I have shown the same as comprising a cylinder 1 having an elongated forward extension 2 carrying a chuck housing 3 within which is disposed the shank 4 of a collared steel 5. This steel is held in its operative position as by a coiled spring tool retainer 6 carried on the housing 3 as by spiral grooves 7 formed in the periphery thereof. Disposed within the cylinder is a bore 8 communicating with a reduced bore 9 and within which is a reciprocable piston 10 having a forwardly projecting striking bar 11. Carried on the rear end of the cylinder 1 is a head 12 carrying a detachable handle 13 within which is disposed a usual spring pressed fluid control valve 14 manually operated by a member 15 pivotally mounted on said handle as at 16.

Disposed within the head 12 are a plurality of stepped bores 17 and 18 within which is reciprocably mounted a fluid controlled distributing valve 19 having a straight cylindrical inner bore 20 adapted to have telescopic engagement with the piston 10 when the same is in its rearmost position. This valve has outer enlarged and reduced cylindrical portions 21 and 22 disposed within the bores 18 and 17 respectively, the rear end of the enlarged portion 21 being beveled as 55 at 23 while a forward radial surface 24

formed at the juncture of the enlarged and reduced portions has a small groove 25 disposed therein to allow actuating fluid to gain access thereto. The valve 19 is somewhat shorter than the combined length of the bores 17 and 18 so that when in its rear position the exhaust port 26 will be opened, but when in its forward position, said exhaust port will be closed to allow the rear and front ends of the cylinder 8 to have communication as by a port 27 leading from a longitudinal passage 28 which terminates adjacent the front end of the cylinder as by the port 29. A passage 30 also allows communication between the passage 28 and the cylinder when the piston 10 is in either its forward or rearward position. Live pressure fluid is continuously admitted to the front end of the cylinder from a suitable supply hose 31, and through a chamber 32, a valve controlled port 33, a passage 34 and a port 35. Also communicating with the passage 34 is a small port 36 leading to the forward part of the bore 18 to allow a continuous supply of live pressure fluid to act upon the surface 24.

In the operation of my device it will be assumed that the piston 10 is about to be driven rearwardly by pressure fluid continuously supplied through the passage 34 while the rear end of the cylinder is exhausted through the port 26, the valve 19 being held in its rear position to hold said port open as by continuous supply of live pressure fluid acting upon the surface 24. It is to be noted that the pressure on the bevel surface 23 is also vented to atmosphere as through the passage 30. As the piston moves rearwardly the port 29 will be uncovered and the port 30 closed to allow flow of live pressure fluid to the bevel surface 23 which will overcome the pressure acting upon the surface 24 to force the valve 19 in a forward direction closing the exhaust port 26 and allowing live pressure fluid to act upon the rear end of the piston 10 to drive the same forwardly. The initial impulse given the piston 10 by the continuous pressure in the front end of the cylinder 1 is sufficient to carry the piston to the position shown in Fig. 2. As the piston travels forwardly the port 29 will be closed and expansion of the operating fluid will take place in the rear end of the cylinder with a resultant reduction of pressure. As soon as the valve is thrown, the cylinder is open to exhaust through the port 26, and pas-

sage 28 is also exhausted to atmosphere by way of port 30 in the cylinder. As a result pressure on the bevel surface 23 will decrease until the effective force thereof is less than the effective force acting on the surface 24, which latter force will cause rearward movement of the valve and exhaust fluid through the port 26.

While I have in this application specifically 10 described one form which my invention may assume in practice, it will be understood that this form of the same is shown for purposes of illustration and that the invention may be modified and embodied in various other 15 forms without departing from its spirit or the scope of the appended claims.

What I claim as new and desire to secure by Letters Patent is:

1. A motor comprising a cylinder, a pressure fluid actuated piston reciprocably mounted therein, and fluid distribution means for effecting reciprocation of said piston comprising passage means for supplying live pressure fluid continuously to one end of 25 said piston, and a hollow sleeve valve open from end to end and arranged in axial alinement with said cylinder and through which said piston is slideable, said valve having differential annular pressure areas for allowing 30 actuation of said valve by fluid acting thereon, one of said areas being subjected to constant pressure while an opposed area is subjected to fluctuating pressures.

2. A motor comprising a cylinder, a pressure fluid actuated piston reciprocably mounted therein, and fluid distribution means for effecting reciprocation of said piston comprising passage means for supplying live pressure fluid continuously to 35 one end of said piston, a hollow sleeve valve arranged in axial alinement with said cylinder and open from end to end and having differential pressure areas for allowing actuation of said valve by fluid acting thereon, one of said areas being subjected to constant 40 pressure while an opposed area is subjected to fluctuating pressures, and an exhaust for one end of said cylinder controlled by said valve so as to be opened when the valve is 45 shifted by pressure on said constant pressure area.

3. A motor comprising a cylinder, a pressure fluid actuated piston reciprocably mounted therein, and fluid distribution means for effecting reciprocation of said piston comprising a hollow sleeve valve arranged in axial alinement with said cylinder and having differential pressure areas for allowing actuation of said valve by fluid acting 55 thereon, passage means for supplying live pressure fluid continuously to the forward end of said piston, a passage communicating with said passage means for subjecting one pressure area on said valve to constant pressure, passage means for supplying

pressure fluid to an opposed area on said valve for throwing the same, said latter passage means also supplying fluid to the rear end of said cylinder, and exhaust means for the rear end of said cylinder controlled by 70 said valve.

4. A motor comprising a cylinder, a pressure fluid actuated piston reciprocably mounted therein, and fluid distribution means for effecting reciprocation of said piston comprising a hollow sleeve valve open from end to end and arranged in axial alinement with said cylinder and having differential pressure areas for allowing actuation of said valve by fluid acting thereon, passage means for supplying live pressure fluid continuously to one end of said piston, means for subjecting an area on said valve to live fluid from said passage means, exhaust means for the other end of said cylinder controlled by said valve, and 85 means for subjecting an opposed area on said valve to the variable pressure in the other end whereby said valve is actuated when the expansion of the piston actuating fluid has reached a predetermined point in said latter 90 cylinder end.

5. A motor comprising a cylinder, a pressure fluid actuated piston reciprocably mounted therein, and fluid distribution means for effecting reciprocation of said piston comprising a live fluid supply passage having continuous communication with one end of said cylinder, a hollow sleeve valve open from end to end and arranged in axial alinement with said cylinder through which said piston is slideable during running of said motor and having spaced radially disposed large and small annular pressure areas, a rear cylinder supply passage adapted to allow communication between the front cylinder end and the large area on said valve and which is controlled by said piston, a continuously open passage between said live fluid passage and the small area on said valve, and an exhaust port for the rear end of said cylinder controlled by said valve.

6. A motor comprising a cylinder, a pressure fluid actuated piston reciprocably mounted therein, and fluid distribution means for effecting reciprocation of said piston comprising a live fluid supply passage having continuous communication with one end of said cylinder, a hollow sleeve valve arranged in axial alinement with said cylinder and having spaced radially disposed large and small pressure areas, a rear cylinder supply passage adapted to allow communication between the front cylinder end and the large area on said valve and which is controlled by said piston, a continuously open passage between said live fluid passage and the small area on said valve, an exhaust port for the rear end of said cylinder controlled by said valve, and a passage between the rear end of said cylinder and the supply passage leading thereto and which is 120 125 130

- controlled by said piston to permit exhaust of pressure fluid acting on said large area.
7. A motor comprising a cylinder, a pressure fluid actuated piston reciprocably mounted therein, and fluid distribution means for effecting reciprocation of said piston comprising a live fluid supply passage having continuous communication with the forward end of said cylinder, a valve chamber arranged in axial alinement with said cylinder and forming a continuation of the cylinder bore within which said piston is movable, a hollow sleeve valve in said chamber within which said piston is adapted to move, said valve having an enlarged radial flange and a reduced sleeve portion, the flange having opposed differential pressure areas, a rear cylinder supply passage adapted to allow communication between the front cylinder end and one area on said flange and which is controlled by said piston, a continuously open passage between the live fluid passage and an opposed area on said flange, an exhaust port for the rear end of said cylinder controlled by the sleeve portion of said valve, and a passage between the rear end of said cylinder and the supply passage leading thereto and which is controlled by said piston to exhaust the pressure fluid in said rear cylinder supply passage which acts on the larger of said areas.
8. A motor comprising a cylinder, a pressure fluid actuated piston reciprocably mounted therein, and fluid distribution means for effecting reciprocation of said piston comprising passage means for supplying live pressure fluid continuously to one end of said piston, and a hollow sleeve valve disposed coaxially with said cylinder and within which said piston is adapted to move, said valve having differential pressure areas for allowing actuation thereof by fluid acting thereon, a passage controlled by said piston for conducting fluid from the forward end of said cylinder to the rear end thereof, said passage also being controlled by said valve, a relief port in direct communication with said passage for relieving the pressure on the larger of said valve areas, and an exhaust passage for the rear end of said cylinder controlled by said valve.

In testimony whereof I affix my signature.

ELMER G. GARTIN.
